DEVICE FOR HANDLING CAKES OF ICE AND
DELIVERING SAME IN COMMINUTED
FORM

Frank W. Brady, San Francisco, Calif.

Application October 21, 1946, Serial No. 704,651

4 Claims. (Cl. 241—60)

1

This invention relates to an improved machine for converting cakes of ice into finely divided ice and for discharging such finely divided ice as a continuous stream for discharge at a point spaced a considerable distance from the ice breaking means. In the preparation and shipment of various products, it is usual to place a layer or blanket of finely divided ice over the product when these are packed in a shipping container such as is provided by a truck, refrigerator car, or the like. Heretofore, one of the usual practices employed has been first to convert the ice to finely divided form, storing it as snow ice or the like; subsequently, the snow ice is fed to a suitable device capable of discharging the snow ice at a suitable point of discharge.

The present invention contemplates a unitary machine, capable of receiving a cake of ice as such, and converting the same into ice of a suitable size which is then discharged at a selected point; the machine operates continuously and positively to convert the cake of ice into a suitable form in which it is discharged at such discharge point so that the wastage or loss, heretofore present in the handling and use of snow ice, is obviated.

It is the generally broad object of the present invention to provide a novel and yet relatively simple machine for comminuting continuously a cake of ice into finely divided form and for discharging the fine ice at a selected point of discharge through a flexible hose or other suitable conduit.

An additional object of the present invention is to provide a novel, simple and rugged ice comminuting device capable of converting a cake of ice positively and continuously into finely divided ice which is simultaneously forced through a suitable conduit to a selected point of discharge.

The invention includes other objects and features of advantage, some of which, together with the foregoing, will appear hereinafter wherein the present preferred form of machine of this invention is disclosed.

In the drawings accompanying and forming a part hereof, Figure 1 is a side elevation of a machine embodying the present invention.

Figure 2 is a view similar to Figure 1 with portions of the machine broken away to illustrate the construction utilized.

Figure 3 is a section taken along the line 3—3 in Figure 1.

Figure 4 is a plan view of another machine including a modified form of feeder.

2

Figures 5 and 6 are respectively sections taken along the lines 5—5 and 6—6 in Figure 4.

Referring to the drawings, the machine of the present invention includes a suitable frame, indicated generally by numeral 6, and comprising suitable structure members to provide support for the operating elements described. The machine is preferably mounted upon wheels 7 and castor mounted wheels 8 so it can be moved about from place to place as desired.

Mounted substantially centrally of the frame is a casing structure generally indicated by numeral 5 and having bearings 9 and 10 positioned at opposite ends thereof to support vertically a shaft 11. A V-belt pulley 12 is mounted at the upper end of the shaft to receive a plurality of V-belts 13 which are, in turn, trained about V-belt pulley 14 mounted upon motor shaft 15. An electric motor 16 is mounted upon a side of the casing 5 and is also supported by base 17 on frame 6.

On an upper portion of shaft 11 is mounted ice-breaker drum 18 having a plurality of ice-breaking means such as teeth 19 secured and spaced about the periphery thereof in a well known manner. On a lower portion of shaft 11 is mounted bladed ice impeller means indicated generally by numeral 21 and adapted to receive ice particles broken by the ice-breaker drum and the teeth 19 thereon and to discharge these forcefully.

Casing 5 is preferably fashioned in two portions, 22 and 23. Casing portion 22 surrounds the ice-breaker drum 18 and is open along one side as at 25 to admit a cake of ice. Preferably casing portion 22 is made substantially rectangular in cross section with the rear wall 24 thereof closely adjacent to the ice-breaker drum so that particles of ice jamming between the drum and the casing are forcefully broken. Being non-circular in outline, ice particles, broken from a cake of ice by the drum, do not continue to move about the casing as the drum rotates; instead, they are thrown off forcefully into one of the corners, to break against the casing or to fall back and re-engage the drum.

Casing portion 23, that surrounding the bladed impeller means 21, is preferably circular in outline and includes a tangential outlet indicated generally by numeral 27 to receive ice particles discharged from the bladed impeller means and to pass the ice particles on to a suitable point of discharge through the flexible conduit of hose 28. Casing portion 23 is positioned immediately below casing portion 22 so that ice particles, fall-

ing down past the drum, fall into the bladed impeller means.

To provide for the forceful feed of blocks of ice to the ice-breaker drum, spaced transverse shafts 31 and 32 (Figures 1, 2 and 3) are suitably mounted upon frame 6 and pairs of sprockets 33 and 34 are respectively provided upon the shafts 31 and 32. Shaft 31 is positively driven by a sprocket 36 on one end of the shaft and about which a chain 37 is extended from a gear 38 carried upon a shaft 39 in a speed change device indicated generally by numeral 41. An electric motor 42 is mounted upon an upper portion of the casing 5, a sprocket 43 being provided upon motor shaft 44 and driving a sprocket 46 by a chain 47, sprocket 46 being carried upon a shaft 48 in the speed change device 41. A chain 51 is extended about each of the sprocket pairs 33 and 34, each chain preferably carrying a plurality of spaced lugs 52 thereon to engage and force onward positively toward the ice-breaking drum a cake of ice positioned upon and supported by chains 51.

In operation, the chains 51 are advanced toward the ice-breaker drum at such a rate of speed that a cake of ice, confined between extended transverse walls 50, is forced into the drum positively so that it is always maintained in contact with the drum through opening 25 in the casing 5 and so that the drum is constantly working to abrade and comminute the ice cake. Particles of ice broken from the cake of ice are forcefully batted about between the ice-breaker drum, its several projecting teeth and casing 5 until they are of a fineness sufficient to permit them to fall down into the casing 23 and the bladed impeller means which, rotating at the same speed with the ice-breaker drum, forces them on positively until they are discharged through the tangential outlet 27 into the flexible hose 28.

The use of the lugs on the chains 51 is not absolutely essential although I prefer them since they provide for a more positive feed into the ice-breaker drum.

In that form of device shown in Figures 1, 2 and 3, it is intended that the usual, substantially rectangular cake of ice be fed with one of the narrow sides on the chains 51 so that the ice cake extends vertically for a considerable distance above the chains 51. If desired, however, an ice-breaker drum 18 of less height can be employed if the ice cake is fed in while it is lying upon one of its flat major sides, in which case, the drum 18 should be made of a greater diameter.

In Figures 4, 5 and 6, I have shown another form of the device and more particularly a form of ice cake feeder suited to receive a cake of ice from the level of floor 61 and deliver it positively to the drum. In this form of feeder shafts 62, 63 and 64 are positioned vertically on frame 6 in suitable bearings and along one side of a feed chute structure 66. Shaft 63 is driven from shaft 11 by V-belts 65 passed about pulley 67 on shaft 11 and pulley 68 on shaft 63. Chain 69 is passed about sprockets 71 and 72 on shafts 62 and 63 and chain 74 is passed about sprockets 73 and 75 on shafts 63 and 64 to drive shafts 62 and 64 from shaft 63.

A plurality of toothed feeder sprockets 76 are mounted on each shaft 62, 63 and 64 to engage and move toward the ice-breaker drum a cake of ice fed in against the sprockets. An angularly positioned feeder plate 77 extends upwardly from

the floor to raise an ice cake as it is moved by the sprockets.

To force the ice block against the feed sprockets, a plurality of rollers 81 are provided and 5 are biased by springs 82 to force an ice cake against the feed sprockets, the roller being suitably supported on frame 6 for rotation and for sliding toward and away from sprocket 76 so that, as a cake of ice is fed, it is held against the 10 feed sprockets. It will be recalled that a cake of ice is frequently made by freezing water in a can which tapers from the top to the bottom so the ice can be drawn readily from the can after the water has frozen.

15 From the foregoing, I believe it will be apparent that I have provided a novel and improved form of ice feeder and crusher capable of converting cake ice into snow ice and delivering the latter, as formed, in a continuous stream at a distant point.

I claim:

1. A machine for converting a block of ice into finely divided particles and for discharging said particles in a substantially continuous stream 25 through a hose, said machine comprising a substantially vertical shaft, an icebreaker drum having ice breaking means thereon and mounted on said shaft along an upper portion of the shaft, bladed impeller means mounted on a lower portion 30 of said shaft below said drum to receive ice particles from said drum, a first casing surrounding said drum and having a vertical opening along one side thereof, a pair of spaced conveyor chains extending substantially horizontally and adapted 35 to support a cake of ice, means for moving said chains toward said drum to feed a cake of ice supported on said chains into positive ice breaking engagement with that portion of said drum, exposed through the opening in said first casing, 40 and a second casing circular in cross-section surrounding said bladed impeller means and immediately below the first casing and having a tangential outlet therefrom for ice particles.

2. A machine for converting a block of ice into 45 finely divided particles and for discharging said particles in a substantially continuous stream through a hose, said machine comprising a substantially vertical shaft, an ice breaker drum having ice breaking means thereon and mounted on 50 said shaft along an upper portion of the shaft, bladed impeller means mounted on a lower portion of said shaft below said drum to receive ice particles from said drum, a first casing of substantially rectangular cross-section surrounding 55 said drum and having a vertical opening along one side thereof, a pair of spaced conveyor chains extending substantially horizontally and adapted to support a cake of ice, means for moving said chains toward said drum to feed a cake of ice supported on said chains into positive ice breaking engagement with that portion of said drum, exposed through the opening in said first casing, 60 and a second casing circular in cross-section surrounding said bladed impeller means and immediately below the first casing and having a tangential outlet therefrom for ice particles.

3. A machine for converting a block of ice into 65 finely divided particles and for discharging said particles in a substantially continuous stream through a hose, said machine comprising a substantially vertical shaft, an ice breaker drum having ice breaking means thereon and mounted on said shaft along an upper portion of the shaft, bladed impeller means mounted on a lower portion 70 of said shaft below said drum to receive ice

particles from said drum, a first casing surrounding said drum and having a vertical opening along one side thereof, an inlet member leading to said opening in the first casing from a floor level, a plurality of spaced shafts extending vertically and spaced along said inlet member, feed sprockets on each of said plurality of vertical shafts, means for rotating said shafts in a timed relation with said ice breaker drum, means for forcing an ice cake sliding over said inlet member to engage said sprockets, and a second casing circular in cross-section surrounding said bladed impeller means and immediately below the first casing and having a tangential outlet therefrom for ice particles.

4. A machine for converting a block of ice into finely divided particles and for discharging said particles in a substantially continuous stream through a hose, said machine comprising a substantially vertical shaft, an ice breaker drum having ice breaking means thereon and mounted on said shaft along an upper portion of the shaft, bladed impeller means mounted on a lower portion of said shaft below said drum to receive ice particles from said drum, a first casing surrounding said drum and having a vertical opening along one side thereof, an inlet member leading to

said opening in the first casing from a floor level, a plurality of spaced shafts extending vertically and spaced along said inlet member, feed sprockets on each of said plurality of vertical shafts, means for rotating said shafts in a timed relation with said ice breaker drum, a plurality of spaced rollers opposite said shafts and biased toward said feed sprockets for forcing an ice cake sliding over said inlet member to engage said sprockets, and a second casing circular in cross-section surrounding said bladed impeller means and immediately below the first casing and having a tangential outlet therefrom for ice particles.
